VACUUM CLEANER NOZZLE WITH DETACHABLE BRUSH CARRYING UNIT

Charles H. MacFarland, Cleveland, Ohio, assignor to The Scott & Fetzer Company, Cleveland, Ohio, a corporation of Ohio

Application October 29, 1949, Serial No. 124,291

4. Claims. (Cl. 15—368)

1

This invention relates to a combined suction nozzle and brush for vacuum cleaners and more particularly to a nozzle having a detachable carpet engaging shoe upon which a rotary brush is mounted.

The invention has for an object to provide a brush carrying carpet engaging shoe that has detachable connection to the nozzle body and that provides a mounting for the brush by means of which the brush may be adjusted with respect to the shoe while the shoe and brush are detached from the nozzle whenever such adjustment is desirable to compensate for wear or to obtain the proper projection of the bristles past the face of the shoe.

A further object of the invention is to utilize the spring arms which frictionally engage the end walls of the nozzle to hold the shoe in place as brush mounting members between which the brush may be detachably clamped in various positions of vertical adjustment.

A further object of the invention is to provide simple and conveniently operable means for disengaging the brush driving belt from the fan shaft to permit removal of the shoe and brush and to reengage the belt with the fan shaft after the shoe and brush have been attached to the nozzle.

With the above and other objects in view, the invention may be said to comprise the combined suction nozzle and brush as illustrated in the accompanying drawings and hereinafter described, together with such variations and modifications thereof as will be apparent to one skilled in the art to which the invention pertains.

Reference should be had to the accompanying drawings forming a part of this specification in which:

Figure 1 is a front elevation of a combined suction nozzle and brush embodying the invention, one end portion of the nozzle body being broken away and shown in section;

Fig. 2 is a top plan view of the combined brush and shoe;

Fig. 3 is a front elevation of the carpet engaging shoe and rotary brush detached from the nozzle body;

Fig. 4 is a fragmentary vertical section through an end of the shoe taken on the line indicated at 4—4 in Fig. 5;

Fig. 5 is a vertical section taken on the line indicated at 5—5 in Fig. 4 looking toward the inner face of a brush supporting arm;

Fig. 6 is a plan view of the brush attaching plate on a scale slightly larger than Figs. 4 and 5;

Fig. 7 is a fragmentary axial section through the end of the brush cylinder taken on the line indicated at 7—7 in Fig. 6;

2

Fig. 8 is a fragmentary view showing the belt threader arm positioned over the fan shaft with the belt in position to be engaged with the shaft upon retraction of the threader arm;

Fig. 9 is a front elevation of a modified form of shoe and brush unit;

Fig. 10 is a fragmentary longitudinal vertical section showing one end of the shoe and brush on an enlarged scale;

10 Fig. 11 is a vertical section taken on the line indicated at 11—11 in Fig. 10;

Fig. 12 is a plan view of the brush attaching plate;

15 Fig. 13 is a fragmentary plan view of one end of a brush supporting shoe having integral brush supporting arms; and

Fig. 14 is a section taken on the line indicated at 14—14 in Fig. 13.

The combined nozzle and brush of the present invention is of a type in which the nozzle is attached at its upper end to a fan casing inlet and in which a brush is mounted in the nozzle inlet and driven from the end of the fan shaft which projects into the nozzle.

20 As herein shown, the nozzle body 1, which is of the type adapted to be detachably secured to the inlet of the cleaner fan casing, has a lower portion formed to provide an elongated open bottom brush chamber 2 which has front and rear walls 3 and 4 and end walls 5, the lower edges of which form the margins of the open bottom of the brush chamber. A carpet engaging shoe 6 is mounted on the lower end of the nozzle and this shoe is provided with a marginal

25 upwardly facing channel 7 that receives the lower edges of the walls 3, 4 and 5, the outer flange 8 of the marginal channel engaging the outer faces of the walls 3, 4 and 5. At the ends of the shoe the inner flanges of the marginal channel 7 have extensions 9 to which are attached spring metal arms 10. The lower portions of the arms 10 are substantially upright and the upper end portions 11 thereof are bowed outwardly for frictional engagement with the

30 interior of the end walls 5 of the brush chamber 2 to detachably retain the shoe on the nozzle body. The spring arms 10 also serve to support the ends of a brush cylinder 12 so that the brush cylinder is removable with the shoe from

35 the nozzle body. The cylinder 12 has bristles 13 disposed in helical rows on longitudinally spaced portions of the cylinder. The bristle portions 13 are spaced apart to provide a central pulley portion 14 on the cylinder to receive a driving belt 15 that is adapted to engage an end portion of a fan shaft 16 and to provide a driving connection from the fan shaft to the brush cylinder.

40 The cylinder 12 has a central pulley portion 14 which is adapted to receive a driving belt 15 that is adapted to engage an end portion of a fan shaft 16 and to provide a driving connection from the fan shaft to the brush cylinder.

45 The cylinder 12 has a central pulley portion 14 which is adapted to receive a driving belt 15 that is adapted to engage an end portion of a fan shaft 16 and to provide a driving connection from the fan shaft to the brush cylinder.

50 The cylinder 12 has a central pulley portion 14 which is adapted to receive a driving belt 15 that is adapted to engage an end portion of a fan shaft 16 and to provide a driving connection from the fan shaft to the brush cylinder.

55 The cylinder 12 has a central pulley portion 14 which is adapted to receive a driving belt 15 that is adapted to engage an end portion of a fan shaft 16 and to provide a driving connection from the fan shaft to the brush cylinder.

60 The cylinder 12 has a central pulley portion 14 which is adapted to receive a driving belt 15 that is adapted to engage an end portion of a fan shaft 16 and to provide a driving connection from the fan shaft to the brush cylinder.

65 The cylinder 12 has a central pulley portion 14 which is adapted to receive a driving belt 15 that is adapted to engage an end portion of a fan shaft 16 and to provide a driving connection from the fan shaft to the brush cylinder.

70 The cylinder 12 has a central pulley portion 14 which is adapted to receive a driving belt 15 that is adapted to engage an end portion of a fan shaft 16 and to provide a driving connection from the fan shaft to the brush cylinder.

the brush cylinder the shoe 6 has a cross bar 17 extending between the front and rear channels of the shoe, the bar 17 being in the form of an upwardly facing channel of a width to receive the belt 15 so that when the belt is detached from the fan shaft 16 it will drop into the channel of the bar 17 and be supported in upright position by the bar. The helically disposed bristles 13 preferably have gaps between the central pulley portion 14 and the ends of the cylinder 12 which provide spaces for bars 18 connecting the front and rear channels of the shoe. The bottom faces of the bars 17 and 18 are flush with the bottom faces of the marginal channel 7 of the shoe, providing additional support for the nozzle on a carpet and preventing the carpet from being drawn by suction into the nozzle.

The brush cylinder 12 is connected to the arms 10 of the carpet engaging shoe through attaching plates 19 that are mounted on the ends of the cylinder 12 to turn about the axis of the cylinder. The shoe and brush are attachable as a unit to the vacuum cleaner nozzle and the brush is mounted for vertical adjustment on the upright arms 10 of the shoe. The adjustment is preferably effected by means of selectively engageable projections and socket connections between the arms 10 and attaching plates 19. As illustrated in Figs. 4 to 7 inclusive, each of the plates 19 may be provided with an elongated raised portion 20, the center line of which extends radially. The raised portion 20 is provided with radially spaced transversely elongated sockets in the form of grooves 21 each of which is adapted to receive a transversely elongated projection 22 on the inner face of the arm 10. The sockets 21 and projections 22 extend across the vertical center line of the arm 10, and the elongated projections 22 engaging in the sockets 21 serve to hold the attaching plates against turning movements. The sockets 21 and projections 22 are preferably V-shaped, the sockets 21 being arranged with their apices in radial alignment and the projection 22 of each arm 10 being disposed with its apex at the center of the arm.

When the shoe 6 is detached from the nozzle body the arms 10 can be spread apart to disengage the projections 22 from the sockets 21, and the cylinder 12 can be adjusted to the desired vertical position on the arms 10. When the shoe 6 is secured to the nozzle body the arms 10 are pressed tightly against the attaching plates 19 to securely lock the plates in adjusted position and the attaching plates serve to rotatably support the cylinder 12. The cylinder 12 may be journaled to the attaching plates 19 in any suitable manner. As herein shown the attaching plates 19 are shown attached to reduced ends 23 of a spindle 24, the cylinder 12 being provided with a cup-shaped recess 25 at each end into which the reduced extensions 23 project. The cylinder 12 is mounted on ball bearings 26 mounted in the recesses 25 and positioned on the reduced portions 23 of the spindle.

Each attaching plate 19 has a hub portion 27 projecting into the recess 26 and this hub portion may be provided with a sealing ring 28 to retain oil in the bearing and to prevent entry of dust to the bearing. The attaching plates 19 may be provided with guard flanges 29 that closely overlie the ends of the cylinder 12 to prevent the entry of threads and lint to the end bearings.

In order to remove the shoe and brush from the nozzle it is necessary to free the brush driving belt 15 from the fan shaft 16 and in reas-

sembling it is necessary to reengage the belt with the fan shaft. In order to facilitate the assembling and disassembling, a belt shifting and supporting device of the type disclosed in my Patent No. 2,538,464, granted January 16, 1951 is employed in combination with means carried by the shoe 6 for supporting the belt in an upright position upon assembly of the belt, brush and shoe with the nozzle where it can be engaged by the belt shifting device and moved to a position to receive the fan shaft.

The belt placing device comprises a plate 30 rotatably mounted in an opening in the front wall of the nozzle of the body 1. The plate 30 is provided with peripheral shoulders 31 that engage with a stop pin 32 to limit the turning movement of the plate, and the plate is provided with an outwardly projecting handle 33 by means of which it may be turned.

Projecting from the inner side of the plate 30 into the nozzle body 1 is a belt engaging arm 34 that is provided with a front inner portion 35 which closely overlies the shaft 16 when the arm 34 is in its uppermost position, and a rear outer portion 36 that extends laterally and radially outwardly with respect to the inner portion and which tapers toward its outer end. The arm 34 at one limit of movement has its inner portion 35 positioned to closely overlie the shaft 16, and at its opposite limit of movement is positioned below the shaft 16 and laterally clear of the belt 15. The outer belt engaging face of the arm 34 is convex and the inner face is concave, the concave face of the inner portion of the arm lying closely adjacent the top of the shaft 16 when the arm is moved to its uppermost position.

When the cylinder 12 is mounted on the shoe 6 for insertion into the brush chamber 2 of the nozzle, the belt 15 is supported in the channel 17 as shown in Fig. 3 and projects upwardly above the top of the cylinder 12. After the brush is inserted into the brush chamber the upper portion of the belt 15 is alongside the pointed end 36 of the arm 34 so that when the plate 30 is turned the pointed end 36 of the arm will enter the belt 15 and engage the interior thereof. As the arm 34 swings to its uppermost position the tension of the belt shifts the belt inwardly to the inner portion 35 of the arm where it is in position to receive the fan shaft 16 when the nozzle is attached to the fan casing. To engage the belt with the shaft 16, the plate 30 is turned in the opposite direction to move the arm 34 laterally out of engagement with the belt and permit the belt to engage with the fan shaft 16, and when the plate 30 is moved to its opposite limit of movement the arm is positioned entirely clear of the belt.

In Figs. 9, 10, 11 and 12 an alternative adjustable brush mounting is shown. In this modification the shoe and brush unit is mounted in the vacuum cleaner nozzle in the same manner as in the modification first described, the shoe 6a, arms 10a, brush cylinder 12a, belt 15a and attaching plates 19a corresponding to the shoe 6, arms 10, cylinder 12, belt 15 and plates 19 in the modification first described.

Each arm 10a may be provided with a base flange 40 as shown in Fig. 10 and this flange may be secured by suitable means such as welding to the bottom of the marginal channel of the shoe. The arms 10a are each provided with a pair of vertically aligned openings 41 and 42 which provide sockets to receive correspondingly spaced 75 pairs of projections 43 and 44 or 45 and 46 on

5

the attaching plate 19a which are of a size to fit in the sockets 41 and 42. The projections of each pair 43 and 44 and 45 and 46 are diametrically aligned and each of the four projections 43, 44, 45 and 46 is at a different distance from the axis of the brush. Each arm 10a has two horizontally aligned openings 47 and 48 that are of considerably larger diameter than the sockets 41 and 42 to accommodate either pair of projections 43 and 44 or 45 and 46 when the other pair is engaged in the sockets 41 and 42. Each pair of projections provides two positions of vertical adjustment for the brush. For two adjustments a single pair of projections could be used and the openings 47 and 48 would be unnecessary.

The brush supporting arm may be formed integrally with the carpet engaging shoe if desired. The shoe is preferably formed from a sheet metal blank from which portions are cut away to form the openings through which the brush bristles project and as shown in Figs. 13 and 15, a portion of the sheet metal blank cut as indicated by the dotted lines in Fig. 13 may be struck up from the body of the blank to form integral brush supporting arms 10b.

By mounting the brush cylinder adjustably on the bracket engaging shoe the brush may be accurately positioned with respect to the carpet engaging shoe, and after the shoe is attached to the nozzle body the brush is positively held in its adjusted position with respect to the shoe. By means of the manually operable belt threader, the belt 15 can be quickly and easily attached to or detached from the fan shaft, the brush driving belt cooperating with the spring arms 10 to hold the shoe tightly against the bottom of the nozzle body.

It is to be understood that in accordance with the provisions of the patent statutes, variations and modifications of the specific devices herein shown and described may be made without departing from the spirit of the invention.

What I claim is:

1. A combined suction nozzle and brush for vacuum cleaners comprising a nozzle body having an upper fan shaft receiving portion and a lower portion formed to provide an open bottom brush chamber, a carpet-engaging shoe detachably secured to the lower portion of said nozzle body, a rotatable brush cylinder in said chamber, said cylinder being mounted on said shoe and being removable with the shoe, said cylinder having a central belt receiving portion, an endless belt extending around said cylinder, a manually operable belt shifting and supporting member mounted on the nozzle body and having a belt engaging arm within said body and above said brush cylinder that is movable from a lower disengaged position below the fan shaft and laterally clear of the belt into engagement with the interior of the belt and to an uppermost position overlying the fan shaft, and a belt supporting means carried by the shoe and positioned immediately beneath the belt receiving portion of said cylinder, said means supporting the belt when disengaged from the fan shaft in an upright position within said nozzle where it will receive said arm when it is moved from its disengaged position toward its uppermost position.

2. A combined suction nozzle and brush such as defined in claim 1 in which said belt engaging arm is provided with a convex outer belt engaging face and with an outwardly tapering outer end portion that projects laterally and radially outwardly with respect to the inner portion thereof

6

to guide the belt to said inner portion as the arm is moved to its uppermost position.

3. A shoe and brush unit for vacuum cleaner nozzles comprising an elongated carpet engaging shoe having upright spring arms adjacent its ends, each bendable to permit movements thereof longitudinally of the shoe, a rotatable brush, and means for detachably and adjustably mounting said brush on said arms comprising two attaching plates, one secured to each end of the brush and rotatable with respect to the brush about the axis thereof, and a plurality of projection and socket connections, one of said projection and socket connections being located between each 10 attaching plate and its adjacent arm and releasable by bending the arm, the projections being in the form of pins carried by the attaching plates and the sockets being in the form of openings in the upright arms in which the pins fit, each attaching plate having two pairs of identical pins, with the pins of the two pairs aligned on diameters at right angles to one another, the pins of one pair being spaced apart the same distance as the pins of the other pair and each of the four 15 pins being at a different distance from the brush axis, the upright arms being provided with vertically spaced openings in which the pins of either pair fit and with horizontally spaced openings larger than the pins to receive either pair of pins, 20 the pins being selectively engageable with the sockets to support the brush in different positions of vertical adjustment with respect to the shoe.

4. A combined suction nozzle and brush for 35 vacuum cleaners comprising a suction nozzle body having upstanding front, rear and end walls providing an elongated open bottom brush chamber, an elongated rigid carpet engaging shoe shaped to conform to the open bottom of said elongated 40 chamber, said shoe having a narrow continuous marginal portion closely underlying the bottom edges of said walls that is provided with an upstanding continuous marginal flange slidably engaging the exterior faces of said walls, said shoe 45 having upright resilient arms attached at their lower ends to the shoe adjacent its ends and flexible longitudinally of the shoe, said arms having longitudinally bowed upper end portions pressing against the inner faces of said end walls to detachably secure the shoe to said body, a rotatable brush detachably connected at its outer ends to said resilient arms below the upper wall engaging portions thereof, and means to adjust the vertical position of the brush with respect to the shoe.
